UNITED STATES PATENT OFFICE.

JOHN E. CREMEN, OF WASHINGTON, DISTRICT OF COLUMBIA.

DESIGN FOR A BUTTON OR PIN.

SPECIFICATION forming part of Design No. 26,059, dated September 22, 1896.

Application filed July 24, 1896. Serial No. 600,443. Term of patent 7 years.

To all whom it may concern:

Be it known that I, JOHN E. CREMEN, a citizen of the United States, residing at Washington, in the District of Columbia, have invented a certain new and original Design for Buttons and Pins; and I do declare the following to be a full, clear, and exact description of the invention, reference being had to the accompanying drawings, and to the figures of reference marked thereon, which form a part of this specification.

My invention relates to buttons and pins.

The leading feature of my design consists of a button, its shape or configuration being substantially as shown in the drawings.

In the accompanying drawings, Figure 1 is a plan view, enlarged, and Fig. 2 is a side view, of the same.

Referring to the drawings, 1 designates the irregularly-formed mass of metal, and 2 the shank upon which it is mounted.

A pin is shown in dotted lines, and such pin may be employed in lieu of the shank 2 without departing from the spirit of my invention.

What I claim is—

The design for a button or similar article as herein shown and described.

In testimony whereof I affix my signature in presence of two witnesses.

JOHN E. CREMEN.

Witnesses:

J. B. McGIRR,
PHILIP F. LARNER.
